REFRIGERATING APPARATUS

David E. Maccabee, Dayton, Ohio, assignor, by
mesne assignments, to General Motors Corporation, a corporation of Delaware

Application September 1, 1928, Serial No. 303,598
Renewed March 22, 1933

5 Claims. (Cl. 62—3)

This invention relates to refrigerating apparatus and particularly to arrangements for controlling the circulation of refrigerant in such apparatus.

One of the objects of the invention is to provide an improved control system particularly adapted to multiple installations which automatically prevents the circulation of refrigerant in such unit or units of the system as do not need refrigeration.

Another object of the invention is to provide an improved refrigerating system in which one condensing element supplies a number of evaporating elements with refrigerant and automatically maintains each of them at a predetermined temperature limit independent of the remaining elements.

Further objects and advantages of the present invention will be apparent from the following description, reference being had to the accompanying drawing, wherein a preferred form of the present invention is clearly shown.

In the drawing:

Fig. 1 is a diagrammatic representation of one form of refrigerating system arranged in accordance with my invention; and

Fig. 2 is a vertical section of a control valve.

It has been previously proposed to provide a number of evaporators which are supplied with refrigerant from a common condensing element and to operate the system so as to maintain the different evaporators at different temperatures. None of the systems of this character of which I am aware have proved completely successful because the different evaporators are not entirely independent of each other and because the condensing element does not circulate refrigerant through the various evaporators in accordance with the refrigerating demand upon each. The difficulties experienced have been the more pronounced in cases in which it is sought to maintain widely different temperatures. My invention is concerned with providing a simple, economical and reliable system which will satisfactorily maintain widely different temperatures and in which the various refrigerating elements are operated absolutely independently of one another.

Referring to the drawing 10 designates in general a condensing element for withdrawing gaseous refrigerant from a vapor conduit 11, liquefying the refrigerant and delivering it to a liquid supply conduit 12. The condensing element may be of any desired type, for example it may include the usual motor 14, compressor 15 and condenser 16, the motor being actuated in response to the

pressure within the conduit 11 by means of an automatic switch 18 which connects the motor to power mains 19. Evaporators 20 and 21 are connected in parallel between the liquid supply conduit and the vapor exhaust conduit 11 for cooling compartments 20a and 21a. The evaporators are connected to the conduit 11 by means of independent outlet conduits 23 and 24. Preferably each of the evaporators is of the flooded type and includes a reservoir for liquid refrigerant which is kept at a constant level therein by means of a float valve, not shown herein but fully disclosed in the patent to Osborn 1,556,708, October 13, 1925.

In the outlet of each evaporator, at any suitable point between the evaporator proper and the conduit 11, is placed a shut-off valve 26 or 28, each represented diagrammatically as having a valve casing 30, a valve stem 31, and a flexible metal bellows 32 sealed to the casing and to the valve stem to act as a packing. Each of the valves is positively actuated either to closed or to fully open position in response to the pressure existing within its corresponding evaporator by any suitable mechanism herein illustrated as including the following. The valve stem is mounted at the free end of a third class lever 34 pivoted at 35 and urged down to close the valve by means of an adjustable spring 36. Between the pivot and the valve stem the lever carries an armature 37 near which is placed the core of an electromagnet 38 which may be energized by current from the mains 19 through the leads 39 and 40. Each lead 39 includes a switch 41 or 42 for making and breaking the circuit through the electromagnet. This switch may be constructed as shown in the application of Jesse G. King, Serial No. 124,160, filed July 22, 1926, now Patent 1,805,701, issued May 19, 1931, and is diagrammatically represented as including a flexible metal bellows 44, connected to the outlet conduit 23 or 24, and which closes the switch when the pressure in the conduit and consequently in the evaporator is above a certain high value and opens the switch when the pressure is below a certain low value. The value of the pressure at which the switch will open or close can be regulated as is well known in the art by adjusting spring means diagrammatically represented by the spring 45.

In Fig. 2 I have shown the particular form of construction which I prefer for the shut-off valves 26 and 28 which are described above in connection with the diagram shown in Fig. 1. A valve casing 130 is provided with an inlet opening 131

50

55

and an outlet opening 132, the passage between these openings being controlled by a stop valve 133 cooperating with the valve seat 134. A closed housing 135 of non-magnetic material is hermetically sealed to the casing 130 in any suitable manner and contains a magnetic plunger 136, which carries the valve 133, and which is urged downwardly to close the valve by a spring 137 in the housing. A solenoid 138 surrounds the housing 135, being placed in a casing 139, also secured to the valve seat. Electric connections 140 are made in the casing 139 and are adapted to be connected with the leads 39 and 40 for energizing the solenoid. It will be understood that when the solenoid is energized the valve will be suddenly opened and that when the solenoid is de-energized the valve will be abruptly and positively closed.

The system above described operates as follows: Assume for example, that it is desired to maintain the temperature of evaporator 20 between the limits of -3° and 14° F. If sulphur dioxide be used as refrigerant, the switch 41 will be set to close (which opens the valve 26) when the pressure in conduit 23 is atmospheric (0 pounds per square inch gauge) at which pressure the temperature of the evaporator will be 14° F. The switch will be set to open when the pressure is a vacuum of 10 inches of mercury, corresponding to a temperature of -3° F. Thus whenever the evaporator reaches its maximum permissible temperature, the valve 26 will open to permit refrigeration, and this valve will remain open until the evaporator 20 has reached its minimum permissible temperature at which time it will be abruptly and positively closed. If the evaporator 21 is to be maintained at temperatures between 35° and 50° F. the switch 46 would be set to close, and thus open the valve 28, at a pressure of about 18 pounds per square inch gauge, and to open, and thus close the valve 28, at a pressure of about 9 pounds per square inch gauge.

Whenever either switch 41 or 42 is closed and consequently whenever either valve is open, the pressure of the vaporized refrigerant in the vapor conduit 11 closes the switch 18 to operate the compressor, which will then evaporate refrigerant in such evaporator or evaporators as are in communication with conduit 11. The compressor will continue to operate as long as refrigeration is required in either compartment and as soon as the refrigeration demand of either compartment has been satisfied the switch 41 or 42 will open and thus close abruptly the corresponding shut-off valve. This will completely close the outlet of the evaporator independently of the condition of the rest of the system. Whenever the refrigeration demand of all of the evaporators has been satisfied, all of the shut-off valves will be closed and the compressor will immediately reduce the pressure in the conduit 11 to a point at which the switch 18 will open to stop the compressor.

It is thus apparent then that refrigerant will be circulated in any evaporator whenever there is a demand for refrigeration and that as soon as this demand is satisfied the circulation of refrigerant will cease whether or not refrigerant is being circulated in another evaporator. Also due to the snap action of the shut-off valves, each

valve will at all times either fully open or fully close the outlet conduit of the corresponding evaporator. When any valve is open it will remain fully open as long as there is any demand for refrigeration and refrigerant can therefore be circulated at the maximum rate as long as refrigeration is required.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising in combination an evaporator, means for withdrawing gaseous refrigerant from the evaporator, a valve for controlling the outlet of the evaporator, means including a magnetic device for positively opening and positively closing the valve and means responsive to the pressure within the evaporator for energizing the magnetic device.

2. A refrigerating apparatus including an evaporator, means for withdrawing refrigerant from the evaporator, resilient means constantly tending to close the outlet of the evaporator, electromagnetic means for overcoming said resilient means to open the outlet of the evaporator, and means for energizing said electromagnetic means.

3. A refrigerating apparatus including a closed refrigerant circuit including a compressor, a condenser and an evaporator, an enclosed electromagnetic valve means sealed to the closed circuit for controlling the flow of refrigerant through the evaporating means, and switch means located without the closed refrigerant circuit for controlling the energization of the enclosed electromagnetic valve means.

4. A refrigerating apparatus including a closed refrigerant circuit including refrigerant liquefying means and refrigerant evaporating means, valve means for controlling the flow of refrigerant through said refrigerant circuit at the outlet of the evaporating means, spring means for resiliently urging said valve to closed position to shut off the discharge of refrigerant from the evaporating means, electromagnetic means acting upon said valve means to overcome said spring means to open the valve, said valve means and said spring means being located within the closed refrigerant circuit and hermetically sealed therein, an electric circuit for supplying electric energy to said liquefying means and said electromagnetic means, and switch means in said electric circuit for controlling the energization of said electromagnetic means to open said valve means.

5. A refrigerating apparatus including a closed refrigerant circuit comprising a compressor, a condenser and an evaporator, valve means enclosed within and hermetically sealed within the closed circuit for controlling the flow of refrigerant through the evaporating means, an electromagnet for operating said valve means, and switch means located without the refrigerant circuit for controlling the energization of the electromagnet and thereby the actuation of the valve means.
